UNITED STATES PATENT OFFICE.

ELWIN H. HALL, OF PAWHUSKA, OKLAHOMA.

RAIL-JOINT.

1,110,200.

Specification of Letters Patent.

Patented Sept. 8, 1914.

Application filed November 22, 1911, Serial No. 661,731. Renewed February 12, 1914. Serial No. 818,370.

To all whom it may concern:

Be it known that I, ELWIN H. HALL, a citizen of the United States, residing at Pawhuska, in the county of Osage and State of Oklahoma, have invented new and useful Improvements in Rail-Joints, of which the following is a specification.

This invention relates to rail joints, and has for an object to provide means whereby the rail ends can be securely connected together without the provision of the old and well known forms of fish plates.

Another object of the invention is to provide a reversible connecting member for connecting the rail ends together and for forming an effective tread surface at the joint between the ends and for positively preventing the sagging of the rail ends under the weight of the rolling stock.

In the drawing, forming a portion of this specification and in which like numerals of reference indicate similar parts in the several views:—Figure 1 is a side view of the rail joint. Fig. 2 is a longitudinal section therethrough. Fig. 3 is a vertical section on line 3—3 of Fig. 1. Fig. 4 is a view similar to Fig. 2 showing a slightly modified form of the invention. Fig. 5 is a perspective view of the tie plate shown in the preferred form of the invention. Fig. 6 is a perspective view of the tie plate shown in the modified form of the invention.

The rail joint includes rail ends or sections A and B which are identically constructed, each being provided at its ends with a rabbeted portion or recess 1, the vertical shoulders 2 thereof being extended in the direction of the ball of the rail, as shown.

The recesses 1 in the ends of the rail sections are adapted to aline with each other so that in their entirety they will present a substantially rectangular receiving space for the tie plate 3. The tie plate conforms exactly with the shape of the receiving recesses, and as illustrated, it is provided with identical parallel tread surfaces 4 and 5. The tie plate is arranged in the recesses of the rail sections so that one of the tread surfaces of the plate will come flush with the

tread surfaces on the ball portions of the rail sections. The webs of the rail sections are provided with passages 6 which are adapted to aline with the elongated passages 7 in the tie plate. The usual fastening bolts 8 are extended through the alining passages in the rail sections and tie plate respectively so as to effect an extremely rigid joint between the rail sections. By providing the tie plate 3 with the parallel surfaces 4 and 5 the plate is capable of being reversed so that when one of its tread surfaces is worn the plate can be adjusted to expose the other surface.

In the modified form of the invention shown in Fig. 4, the rail sections C and D have formed therein recesses 9, each of which being provided with an end portion 10 having the oppositely inclined shoulders 11 and 12. The tie plate 13 in this form of the invention has its ends provided with V-recesses 14, the walls of which being designed to engage against the shoulders 11 and 12, as shown. The lower shoulders 12 on the portions 10 serve to prevent the tie plate from moving upwardly out of its intended position. The upper shoulders 11 of the portions 10 serve to support the tie plate and when the plate is associated with the rail ends so that the worn tread surface 80 thereof is innermost the shoulders 11 serve to compensate for the wear at the ends of the tie plate and the shoulders thereby operate to maintain the exposed tread surface 85 of the tie plate in the same general plane with the tread surfaces of the balls of the rails.

I claim:

1. Rail sections having recessed ends, a reversible rail tread plate having parallel surfaces adapted to be singly presented to form a tread surface at the joint between the rail sections, the said tie plate having elongated slots therein, and fastening devices extending through the rail sections and through the said elongated slots in the tie plate.

2. Rail sections having recessed ends, a reversible rail tread plate having parallel surfaces adapted to be singly presented to

form a tread surface at the joint between the rail sections, the said recesses having walls of V-configuration, the said tie plate having recesses receiving the V-portions on the walls of the first recesses, and fastening devices connecting the rail sections with the tie plate.

In testimony whereof I affix my signature in presence of two witnesses.

ELWIN H. HALL.

Witnesses:

GEORGE G. LA MOTTE,
WILLIAM H. HALL.
